UNITED STATES PATENT OFFICE.

JOHN B. WARING, OF EAST ORANGE, NEW JERSEY, ASSIGNOR TO WARING PATENTS COMPANY, OF NEW YORK, N. Y., A CORPORATION OF NEW YORK.

REDUCING-VALVE.

No. 800,961.

Specification of Letters Patent.

Patented Oct. 3, 1905.

Application filed March 11, 1904. Serial No. 197,733.

To all whom it may concern:

Be it known that I, JOHN B. WARING, a citizen of the United States, residing at East Orange, in the county of Essex and State of New Jersey, have invented certain new and useful Improvements in Reducing-Valves, of which the following is a specification, reference being had therein to the accompanying drawings, forming a part thereof.

10 My invention relates to valves adapted for the regulation or reduction of pressures and for controlling the flow of a fluid from a higher to a lower pressure, so as to produce a uniform predetermined lower pressure; and 15 my invention has for its objects generally simplicity and compactness of construction and uniformity and reliability of operation.

My invention includes the employment of movable valve-actuating means subjected to 20 the pressure of the low-pressure chamber, this movable valve-actuating means including means for opposing such low pressure and also including rotation-restraining means and of a rotatable valve member controlling the 25 valve and having a helical engagement with the valve-actuating means, so that the motion of the valve-actuating means will be converted into rotary movement of the valve member.

30 My invention also includes the arrangement of the valve member and valve-actuating means so that one will telescope within the other.

My invention also includes the provision 35 of a stationary socket for the valve member with which the valve member has a threaded engagement, so that the rotary movement of the valve member is converted into axial movement thereof, and the helix last mentioned being of considerably less pitch than that of the engagement of the valve-actuating 40 means and rotary valve member, so that the axial movement of the valve member is of considerably less extent than the movement of the valve-actuating means.

45 My invention also includes various improvements in the construction of the parts and in combinations thereof.

I will now describe the devices illustrated 50 in the accompanying drawings and embodying my invention and will thereafter point out my invention in claim.

Figure 1 is a vertical central section of a valve embodying my invention. Fig. 2 is a

horizontal section thereof on a plane indicated by the line 2 2, Fig. 1. Fig. 3 is a horizontal section thereof on the plane indicated by the line 3 3, Fig. 1.

The valve shown in the figures is designed for the reduction of extremely high pressures, 60 such as are encountered in the evaporation of liquefied gases.

The valve-easing comprises a rectangular casting or body *a* and a tubular piston-chamber *b*. The body *a* has a high-pressure duct 65 or passage comprising a high-pressure inlet *c* and a high-pressure chamber *d* and also has a low-pressure outlet *e*. A low-pressure chamber *f* is formed by the lower portion of the piston-chamber *b* and is connected to the 70 low-pressure outlet by the duct 35, and the passage of fluid from the high-pressure duct or chamber *d* to the low-pressure chamber *f* is controlled by a reciprocating needle-valve 75 *h*, coacting with a nipple *g*, having a restricted orifice and screwed into a threaded boring through the upper wall of the body *a*. This valve-nipple has a diametric slot at its enlarged lower end to receive a screw-driver or other implement to effect its insertion and 80 removal and is readily accessible through a threaded orifice in the bottom of the valve-body, this orifice being closed by a removable screw-cap 5.

The valve member has a threaded part 12 85 above the needle-valve *h*, this threaded part passing through a threaded socket 7 in a bracket 6, extending up from the body *a* into the low-pressure chamber. Above the threaded part 12 the valve member has an 90 enlarged cylindrical part 14, provided with helical slots 15 of large pitch, three of such helical slots 15 being shown, and these helical slots coact with a nut 22, carried by the piston 16 and convert the reciprocating 95 movement of the piston into rotary movement of the valve member, and the rotary movement of the valve member screws the valve member up and down in the threaded socket 7 and opens and closes the valve, it 100 being noted that the nut 22 has a guide-rod 8 secured therein and extending down into an elongated guide-boring 20, formed in the bracket 6, and down into a vertical column 32 in the body *a*, this guide-rod restraining 105 rotation of the nut 22.

The piston is of double form to assure tightness and long bearing, the two parts *i*

and i' being connected by a neck j , within which and the lower piston i is formed a hollow cylindrical recess to receive the enlarged helically-slotted cylindrical part 14 of the valve member. Each part of the piston is provided with suitable packing-cups. The packing-cup 25 of the lower piston i is held up against this piston by a washer 27, against which the nut 22 is clamped, this nut 22 being at its upper portion screwed up over a threaded neck extending down from the lower piston. The packing-cup 26 of the upper piston i' is held down against the upper piston by a washer 28, against which is clamped a nut 24, having a rounded or spherical upper-surface and screwed down over a threaded stud extending up from the upper piston i' . The fluid-pressure within the low-pressure chamber f and exerted upward against the piston is opposed by a resisting device shown as consisting of a helical compression-spring 23, which at its lower end presses against the rounded upper surface of the nut 24 and at its upper end presses against a shouldered nut 31 on the adjusting-screw 30, this adjusting-screw being socketed with freedom of rotation in the upper head k of the piston-chamber b and having an enlarged shoulder 33 bearing against the lower face of such head and having flat portions at its upper projecting end for engagement with a wrench or suitable rotating means. The strength of this resisting-spring may be adjusted by rotating the adjusting-screw 30, the other parts being held from rotation by the guide-rod 8 and the pressure of the spring. The rounded upper surface of the upper piston-nut 24 assures a centered thrust of the spring.

The upper part of the piston-chamber b above the piston is open to the outer or atmospheric pressure, and this atmospheric pressure exerted downward on the piston is opposed to the fluid-pressure in the low-pressure chamber f exerted upward against the piston. The downward thrust of the resisting device or spring 23 is so adjusted that this thrust, with the atmospheric pressure,

will close the valve h when the predetermined pressure is attained in the low-pressure chamber. A diminution of pressure in the low-pressure chamber will result in an opening movement of the valve, promptly followed by a closing of the valve when the predetermined pressure is attained.

It will be noted that the piston, the nut 22, engaging the helical slots 15, the guide-rod 8, and the pressure-resisting means, including the spring 23, comprise movable valve-actuating means subjected to the pressure of the low-pressure chamber f and including means for opposing the pressure of the low-pressure chamber and also including rotation-restraining means.

It is obvious that various modifications may be made in the constructions shown and above particularly described within the spirit and scope of my invention.

What I claim, and desire to secure by Letters Patent, is—

A reducing-valve comprising a valve-body having a high-pressure chamber, a high-pressure inlet, a cylindrical low-pressure chamber, an outlet for the low-pressure chamber, and a high-pressure duct leading to the low-pressure chamber, a valve arranged to control the duct, a valve member arranged to control the valve, a hollow piston in the cylindrical chamber and secured to the valve member, the piston and cylindrical chamber having a helical engagement, a bracket extending from the valve-body into the cylindrical chamber and having a bore and also a threaded socket, the valve member having a threaded portion of different pitch than said helical engaging members and engaging the socket, and a rod carried by the piston and movable in the bore in the bracket.

In testimony whereof I have affixed my signature in presence of two witnesses.

JOHN B. WARING.
